CLEANING PAD

George Halvatzis, Flushing, N.Y., assignor to Anton Products Corporation, New York, N.Y., a corporation of New York

Filed Jan. 5, 1965, Ser. No. 83,279

Term of patent 14 years

(Cl. D9—2)

FIG. 1

FIG. 2

FIG. 1 is a front perspective view of a cleaning pad showing my new design; and

FIG. 2 is a rear perspective view thereof.

The dominant features of my design reside in the full line showing of the handle element in association with the conventional pad element, which element is shown in broken lines. It is to be understood that the surface ornamentation shown partially on the drawing is intended to cover the entire surface indicated thereby.

I claim:

The ornamental design for a cleaning pad, substantially as shown and described.
